FUSE

Carl E. Mosley, Richmond Heights, Mo., assignor
to W. N. Matthews Corporation, St. Louis, Mo.,
a corporation of Missouri

Application September 24, 1938, Serial No. 231,489

6 Claims. (Cl. 200—121)

This invention relates to a fuse, and with regard to certain more specific features, to a secondary or low-tension fuse.

Among the several objects of the invention may be noted the provision of a fuse in which a fusible element, both before and after operation of the fuse, remains enclosed and which is provided with indicating means whereby a blown condition may be recognized despite the enclosed condition; the provision of a fuse of the class described in which the indicator is more reliable in operation and more distinctively visible than heretofore; the provision of apparatus of the class described which will not short-circuit under any conditions of operation; and the provision of apparatus of this class which is simple and economical. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

25 In the accompanying drawing, in which is illustrated one of various possible embodiments of the invention,

Fig. 1 is a side elevation of a fuse embodying the invention, showing the parts in unblown condition;

Fig. 2 is a vertical section taken on line 2—2 of Fig. 1; and,

Fig. 3 is a front elevation wherein the parts are shown in blown and indicating position.

35 Similar reference characters indicate corresponding parts throughout the several views of the drawing.

It is desirable on a secondary fuse to have an indication of any fused condition. Some solutions to a problem of providing an indicator have resulted in constructions wherein the enclosures have been arranged to be only partially sealed, by reason of the requirement for an endwise projection from the enclosure of an indicator means, such as a spring. Such a construction does not permit of sealing the enclosure as tightly as is desirable, with the result that water may enter and interiorly swell the fibre of the enclosure, and hence impair its reliability of operation. Fur-

thermore, such constructions, by reason of the expulsive action which occurs by reason of the loose-end construction, sometimes cause the fuse leader ends to separate entirely so that dangling portions become dangerous in forming short circuits with surrounding wires. Even when no ex-

pulsive action occurs, such constructions in any event cause elongation between the separated ends of the link leaders, thereby permitting the fuse as a whole to sag into a possibly dangerous position. Furthermore, the constructions require a more or less detailed examination to determine their blown condition.

The present invention overcomes the above difficulties.

Referring now more particularly to Fig. 1, there are shown at numerals 1 and 3 flexible leaders composed of braided conducting wires, between which the fusible element 27 is placed.

Surrounding the element 27 and inner ends of the leaders 1, 3 is a tubular member 5, preferably made interiorly of horn fibre or the like. Pressed with a relatively tight fit over the upper end of the tube 5 is a metallic conducting cap 7 from the end of which extends a nipple 9. The nipple 9 is crimped into tight gripping contact with the leader 1, as indicated at 17.

At the lower end of the tube 5 is a second cap 11 which is tightly forced on the tube 5 and which has a nipple 13. The nipple 13 is crimped tightly to grip the leader 3, as indicated at 15.

The caps 7 and 11 are prevented from rotating or moving endwise with respect to the tube 5 by means of set screws 19 and 21 respectively. It will be understood that other forms of holding means may be used, such as screw caps, notched means or the like. The importance of the holding means 19, 21 for the caps 7, 11 is that thereby relative rotation between the leaders 1 and 3 is prevented, the leaders being held (crimped) to parts attached to the caps.

It will be understood that the nipples 9 and 13 may be integral with the caps 7 and 11 respectively, as shown, or that they may be separate but fastened, as by soldering or the like. The container formed by parts 5, 7, 11, 9, 13, 15 and 17 is weather-proof.

About the inner ends of the leaders 1 and 3, collars 23 and 25 respectively are crimped to hold in position the fusible element 27. Before crimping, the ends of the fusible elements are thrust in next to the strands of the leaders 1 and 3, thus making an efficient electrical connection. The fusible element 27 is preferably made of relatively heavy copper or the like.

Outside of the tube 5 is arranged a shunt wire 29, preferably of relatively small cross section and composed of stainless steel or the like. This wire is held at its upper ends in electrical connection with the cap 7, as by means of the set screw 19 and extends downwardly to make elec-

trical contact with the nipple 13 as by means of solder 31.

The shunt wire 29 passes through an outwardly located tube 33, preferably formed of Bakelite, fibre or the like and through a spring 35. The spring 35 is also held in position at its lower end as by means of the solder 31 and at its other end is threaded into the tube 33 to support the tube. As shown in Figs. 1 and 2, the shunt wire 29 is 10 arranged parallel to the tube or case 5 so that the spring 35 is flexed and the indicator tube is held in a position parallel to and against the tube 5.

Operation of the device is as follows, assuming 15 that the leaders 1 and 3 are fastened into a suitable low-tension electrical circuit, preferably a secondary circuit:

The fusible conducting element 27 normally carries the major portion of the current until the 20 current increases to a point where this element melts. Instantly the full current passes through the stainless steel shunt wire 29, which melts and releases the tell-tale or indicator tube 33. Under the straightening action of released spring 35, 25 this tube 33 rises to a position perpendicular to the tube 5, as indicated in Fig. 3. The right-angular relationship between the tubes 33 and 5, after blowing, as compared with the parallel relationship before blowing, provides a definite indication 30 of the fused condition of the device.

Ordinary action will not move either of the caps 7 or 11 from the tube. Thus, the distance between the caps remains constant and the assembly of leaders 1 and 3 with the tube 5 is as 35 short after blowing as before. Therefore the device does not sag between the circuit contacts which hold it, nor will any loose wires dangle.

Furthermore, since the caps 7 and 11 have no relative motion with respect to the tube 5, they 40 can be made with the desired tight fit, so that, taken in connection with the squeezing necessary to make the crimps 15 and 17, the inside of the tube 5 is substantially protected against inward leakage of water. The inability of the caps 7 45 and 11 to rotate relatively prevents inadvertent twisting of the fusible element 27.

It is to be understood that the actual diameters of wire 27 and wire 29 are selected so that fusion of wire 27 takes place under the desired electrical 50 conditions, and so that the fusion of wire 29 takes place after the fusion of wire 27. In order to accomplish this end, wire 27 will ordinarily be larger than wire 29, although not necessarily so.

It is also to be understood that the device is 55 useful when the shunt wire 29 fuses at the same time that the fusible element melts, or even when the wire 29 fuses ahead of the fusible element 27. It is only necessary that the fusion of wire 27 be insured when the signal indicates such a condition. In practice, so far as the ordinary observer is concerned, the signal means will be set to indicate a fused condition substantially at the time that the fusible element 27 melts.

If desirable, the outside of the tubes 5 and 33 60 may be made luminescent by suitable means, such as by applying a luminescent paint. This would provide an indication at night of the relative positions of the tubes. Or, merely the tube 33 may be made luminescent, in cases where its absolute position has meaning to an inspector.

It is to be understood that, although the tube 5 is interiorly composed of horn fiber or the like, it may be made up with an exterior surface of Bakelite or the like, or it may be made of other 70 suitable material. The material of which the

tube 33 is made may also have mechanical equivalents.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as 10 illustrative and not in a limiting sense.

I claim:

1. A fuse comprising a fusible element, a non-conducting, weather-proof and completely enclosing container about said fusible element, signal 15 means externally of said container, a shunt conductor externally of said container and electrically shunting the fusible element, said shunt conductor being adapted to fuse substantially when the fusible element fuses, and biased signalling means held by the shunt means in one position under unfused conditions of the shunt means, and movable to a second position under fused conditions of the shunt means.

2. A fuse comprising a pair of spaced, flexible 25 leaders, a fusible element joining said leaders, a non-conducting, weather-proof and complete enclosure about said fusible element and joined to said leaders in a weather-proof manner and permanently to hold them at a predetermined spacing, signal means externally of said container, a shunt conductor externally of said container and electrically shunting the fusible element, said conductor being adapted to fuse substantially 30 when the fusible element fuses, and biased signalling means held in one position under unfused conditions of the shunt, whereby it moves to a second position under fused conditions of the shunt conductor.

3. A fuse comprising a pair of leaders, fusible 40 means connecting said leaders, a tubular container surrounding said fusible element and attached to the leaders, said container being non-conducting between the leaders, a tubular signalling element externally of the container having 45 a position parallel to and adjacent the container and a second position at an angle thereto, a coil spring fastened to the signalling element and biasing the signalling element from its parallel to its angular position, and a shunt wire electrically connected between said leaders and threading the tubular signalling element.

4. A fuse comprising a pair of leaders, fusible 50 means connecting said leaders, a tubular container surrounding said fusible element and attached to the leaders, said container being non-conducting between the leaders, a tubular signal element externally of the container and having a position parallel to and adjacent the container and a second position at an angle thereto, a coil 55 spring fastened to the signal element and biasing the signalling element from its parallel to its angular position, and a shunt element threading the tubular signal element and when unfused biasing the signal element to its parallel position and when fused releasing the signal element to assume an angular position.

5. A fuse comprising a pair of conducting leaders, a conducting fusible element between the 60 leaders, an enclosing insulating tube surrounding said fusible element, conducting caps tightly and non-rotatably fitted to said tube, parts non-rotatably associated with said caps and crimped to said leaders, a tubular signal outside of said tube and having a first position parallel to the enclos- 65

ing tube and a second one at an angle thereto, a coil spring attached to the signal tube at one end and made fast to a stationary part at the other end, and a shunt wire electrically connected between the leaders and threading the signal tube and said spring.

6. A fuse comprising a pair of conducting leaders, a conducting fusible element between the leaders, collars crimped about the ends of the leaders and fusible element to connect them electrically, an enclosing insulating tube surrounding said fusible element, conducting caps tightly and

non-rotatably fitted to said tube, parts non-rotatably associated with said caps and tightly crimped to said leaders, a tubular signal outside of said tube and having a first position parallel to the enclosing tube and a second one at an angle thereto, a coil spring attached to the signal tube at one end and made fast to a stationary part at the other end, and a shunt wire electrically connected between the leaders and threading the signal tube and said spring.
